HOLE CUTTING TOOL

Lawson A. Smith, Los Angeles, Calif., assignor
to Robert H. Clark, Los Angeles, Calif.

Application August 11, 1943, Serial No. 498,216

4 Claims. (Cl. 77—69)

1

This invention relates to tools and relates more particularly to tools for forming or cutting openings. A general object of the invention is to provide a practical, effective tool of this character that is adjustable to cut openings throughout a very wide range of diameters.

Another object of this invention is to provide a tool of the character referred to in which the cutting parts are easily and quickly adjusted simultaneously.

Another object of this invention is to provide a tool of the character referred to in which the bits or cutting parts are adjusted uniformly or equally to insure accurate tracking in their engagement with the work. The adjusting means of the tool of this invention is positive and the cutting parts are shifted equal distances when the adjusting means is actuated.

Another object of this invention is to provide a tool of the character mentioned embodying simple, effective means for releasably setting or locking the parts in the selected adjusted positions.

Another object of the invention is to provide a tool of the character mentioned in which the cutting parts are on the extreme outer ends of the arms so that the tool is capable of forming openings at or immediately adjacent a projection, shoulder or other obstruction on the work.

Another object of this invention is to provide a hole cutting tool of the character referred to in which the cutting parts are adjustably and replaceably secured in the outer ends of the arms by novel means which do not necessitate projections on the outer ends of the arms.

A further object of this invention is to provide a tool of the character mentioned that is simple and inexpensive to manufacture and which embodies a minimum number of parts.

The various objects and features of my invention will be fully understood from the following detailed description of typical preferred form and application of the invention, throughout which description reference is made to the accompanying drawing, in which:

Fig. 1 is a side elevation of a device embodying the invention. Fig. 2 is an enlarged fragmentary vertical detailed sectional view taken as indicated by line 2—2 on Fig. 1. Fig. 3 is a bottom view of the tool shown in Fig. 1. Fig. 4 is a horizontal detailed sectional view taken as indicated by line 4—4 on Fig. 1 with certain portions appearing in elevation, and Fig. 5 is a side view of the key for adjusting the tool.

The tool provided by my invention may be said

2

to comprise, generally, a body 50, a pair of arms 51 shiftably carried by the body, cutting parts 52 on the outer ends of the arms 51, and means 53 for shifting or adjusting the arms.

5 The body 50 may comprise an elongate shank 54 and a head 55 on the lower end of the shank. In the construction illustrated the head 55 is rectangular in transverse cross section and is provided with a flat lower end. A stem or pilot 56 projects from the lower side of the head 55. A transverse opening 57 passes through the head 55 to receive the arms 51. The opening 57 is preferably rectangular and has flat, smooth walls.

10 The arms 51 pass through the opening 57 of the head 55 and are arranged in side by side relation. The arms 51 are rectangular or square in transverse cross section and their flat sides slide one on the other. The surfaces of the arms 51 ride on the walls of the opening 57 (see Fig. 2). The arms 51 are of the same length and when extended are adapted to project a substantial distance from the head 55.

15 The cutting parts 52 are replaceably secured on the outer ends of the arms 51. The active lower portions of the cutting parts 52 are preferably narrow to make a narrow annular cut in the work. One cutting part 52 has a cutting edge 58 for making the inner wall of the annular cut while the other cutting part 52 has a cutting edge 59 for making the outer wall of the cut. The cutting parts 52 may be secured to the arms 51 in any suitable manner. Dove-tailed grooves 60 are shown formed in the outer ends of the arms 51 to receive the correspondingly shaped cutting parts. Longitudinal slots 61 continue inwardly from the grooves 60 and transverse slots 62 are formed in the arms 51 adjacent the inner ends of the slots 61. Clamp screws 63 are provided to clamp the split end portions of the arms 51 onto the cutting parts 52 to secure the cutting parts.

20 The means for simultaneously adjusting the arms 51 is a feature of the invention. The means 53 includes sets of rack teeth 65 on the opposing inner sides of the arms 51. The sets of teeth 65 are preferably of considerable length and are alike or identical. The teeth 65 extend upwardly from the lower edges of the arms 51 and gradually die out before reaching the upper edges of the arms. While the teeth 65 may be of any selected shape, in the preferred construction illustrated the teeth 65 are V-shaped in cross section.

25 The means 53 further includes an opening 66 in the lower end of the head 55 extending upwardly to the opening 57. A pinion 67 is adapted

to be introduced into the opening 66 to cooperate with the sets of rack teeth 65. The pinion 67 is formed on the end of a stem 68 which in turn carries a suitable handle 69. As best illustrated in Fig. 2 of the drawing, the sets of rack teeth 65 are recessed in the inner sides of the arms 51, leaving a space for the reception of the pinion 67. With the pinion 67 entered through the opening 66 to mesh with the rack teeth 65, rotation of the pinion serves to simultaneously adjust or shift the two arms 51 an equal distance.

Means is provided for setting or locking the arms 51 in the adjusted positions. This means includes a longitudinally extending recessed face 70 in the outer side of one of the arms 51. A screw 71 is threaded through an opening in the wall of the head 55 and is adapted to engage the surface 70. When the screw 71 is tightened the two arms 51 are tightly clamped together in the opening 51 to be positively locked in their adjusted positions.

In the operation of the tool the screw 71 is loosened and the pinion 67 is introduced through the opening 66 to mesh with the rack teeth 65. The pinion 67 is readily turned by means of its handle 69. Rotation of the pinion 67 in one direction simultaneously shifts the two arms 51 inwardly an equal distance and rotation of the pinion 67 in the other direction simultaneously moves the two arms 51 outwardly an equal extent. In this way the arms 51 may be easily and quickly adjusted to position the cutting parts 52 to make a cut of the required diameter. When the adjustment has been made the set screw 71 is tightened to secure the arms in the adjusted positions. A pilot bore is then formed in the work and with the shank 54 engaged in a drilling machine the pilot 56 is engaged in the pilot bore and the tool is rotated so that the cutting parts 52 make an annular cut in the work.

Having described only typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A tool of the character described including a central elongate body, the body having a single transverse opening and an offset passage in it from its lower end communicating with the opening, overlapping arms shiftable in the opening and adapted to project laterally from opposite sides of the body, a central pilot projecting from the lower end of the body, cutting parts on the

projecting portions of the arms, and a single means for simultaneously shifting the two arms equal distances and in opposite directions to vary the distance between the cutting parts and the central longitudinal axis of the body including a key separable from the body and insertable through the passage to engage the arms.

2. A tool of the character described including a body, the body having a transverse opening and a central pilot projecting from its lower end and having a longitudinal opening in its lower end offset from the pilot and which joins the transverse opening, a pair of arms shiftably engaged in the transverse opening in side by side relation to project from opposite sides of the body, cutting parts on the opposed sides of the arms, sets of teeth on the arms, a pinion adapted to be entered in said longitudinal opening to cooperate with said teeth and rotatable to simultaneously shift the arms inwardly and outwardly equal distances, and releasable means for holding the arms in the selected positions.

3. A tool of the character described including a body, the body with a central pilot projecting from its lower end and having a transverse opening and a longitudinal opening offset from the pilot and which joins the transverse opening, a pair of arms shiftably engaged in the transverse opening in side by side relation to project from opposite sides of the body, cutting parts on the arms, sets of teeth on the opposed sides of the arms, a key, a pinion formed on the key adapted to be entered in the longitudinal opening to cooperate with said teeth and then turned to shift the arms inwardly or outwardly, and releasable means for holding the arms in the selected positions.

4. A tool of the character described including a body having a transverse opening therethrough and a key opening connecting with the transverse opening from the lower end of the body, overlapping arms supported by the body with their outer ends projecting laterally from the body, the arms being shiftable inwardly and outwardly in the transverse opening, cutting parts on the outer ends of the arms to be spaced laterally from the body, a central pilot projecting from the lower end of the body, and means for simultaneously shifting the arms inwardly and outwardly equal amounts to vary the distance between the body and the cutting parts, said means including a single rotatable actuating key insertable through the key opening to engage the arms to impart movement thereto.

LAWSON A. SMITH.
